US00D865165S

(12) **United States Design Patent** (10) **Patent No.:** **US D865,165 S**
(45) **Date of Patent:** **** Oct. 29, 2019**

(54) **MEDICAL DEVICE ANCHOR**

(71) Applicant: **Custom Medical Applications, Inc.**,
Johnstown, NY (US)
(72) Inventors: **N. Sandor Racz**, Farmers Branch, TX
(US); **James Shoemake**, Dallas, TX
(US)

(73) Assignee: **Custom Medical Applications, Inc.**,
Johnstown, NY (US)

(**) Term: **15 Years**

(21) Appl. No.: **29/584,674**

(22) Filed: **Nov. 16, 2016**

Related U.S. Application Data

(63) Continuation of application No. 15/039,027, filed as
application No. PCT/US2014/067500 on Nov. 25,
2014.

(57)

CLAIM

The ornamental design for a medical device anchor, as
shown and described.

DESCRIPTION

FIG. 1 is a perspective view showing the design in a
deployed state;

FIG. 2 is a side view thereof;

FIG. 3 is another side view thereof;

FIG. 4 is an end view thereof;

FIG. 5 is another end view thereof; and,

FIG. 6 is another perspective view showing the embodiment
of FIG. 1 in a retracted state.

The broken line showing of parts of the drawings is included
for the purpose of illustrating use and environment and
forms no part of the claimed design.

1 Claim, 2 Drawing Sheets
